COMBINED DENTAL CABINET AND INSTRUMENT TRAY

Marvin Winter, 18 Brook Lane, Great Neck, N.Y.

Filed Apr. 18, 1963, Ser. No. 74,513

Term of patent 14 years

(Cl. D24—1)

FIG. 1 is a perspective view of a combined dental cabinet and instrument tray embodying my new design, the broken lines are shown for illustrative purposes only;

FIG. 2 is a perspective view as seen from the right of FIGURE 1, with the movable parts partially displaced to better illustrate configurational details thereof.

The bottom and rear portions of the design not disclosed are substantially flat and plain.

I claim:

The ornamental design for a combined dental cabinet and instrument tray, as shown and described.
